(57) **CLAIM**

The ornamental design for a motor vehicle body, as shown and described.

DESCRIPTION

FIG. 1 is a left-front perspective view of a motor vehicle according to our novel design;

FIG. 2 is a right-rear perspective view of a motor vehicle according to our novel design;

FIG. 3 is a front view of a motor vehicle according to our novel design;

FIG. 4 is a rear view of a motor vehicle according to our novel design;

FIG. 5 is a left side view of a motor vehicle according to our novel design;

FIG. 6 is a right side view of a motor vehicle according to our novel design; and,

FIG. 7 is a top view of a motor vehicle according to our novel design.

The left and right side views are substantially mirror symmetrical in general appearance to each other.

The bottom view is not ornamental and forms no part of the claimed design.
